United Shoe Machinery Corporation, Flemington, N. J., a corporation of New Jersey

Original application May 10, 1948, Serial No.
26,116. Divided and this application February
23, 1949, Serial No. 77,810

4 Claims. (Cl. 89—37.5)

1

This invention relates to articulated fairings or covers for guns which project from an airplane and is herein illustrated as applied to such a fairing designed to project rearwardly from the fuselage.

It is well understood that guns which are to be remotely controlled for airplane use must be provided with a proper sheath or fairing which will preserve the aerodynamic contour of the plane and be jointed or sectioned to permit movement of the gun. Previously devised structures for this purpose have been provided with sliding overlapping parts which were held together by springs or the like and difficulty has been experienced because of excessive friction between those parts when the gun was turned to extreme positions.

Accordingly an object of the invention is to provide an improved pressure control mechanism for holding the parts of a fairing together.

In accordance with this object a feature of the invention relates to an automatic mechanism for this purpose which holds the parts of the fairing closely together but which relieves the pressure between these parts as they are moved to extreme positions.

These and other features of the invention will best be understood from a consideration of the following specification, taken in connection with the accompanying drawings, in which

Fig. 1 is a side elevation of a gun support with an associated fairing shown in section;

Fig. 2 is a transverse vertical section through a gun adaptor on the line II—II of Fig. 1;

Fig. 3 is a view similar to Fig. 1 but with the guns tilted upwardly; and

Fig. 4 is an enlarged horizontal section, through the tip of the fairing, taken on the line IV—IV at the right end of Fig. 3.

The arrangement to be described is associated with a support for four machine guns 10, mounted upon a two-part adaptor 12 (Fig. 2), the support permitting movement so that they may be pointed in any direction within a 90° cone of fire. The guns are surrounded by a suitable three section, articulated sheath or fairing which preserves the aero-dynamic contour of the airplane. In this fairing the inner section which, for convenience, will be called a ball 14 (Fig. 1), comprises a zone through a sphere. Associated with this is a member which will be called a ring 16 and a bullet-shaped point portion 18 hereinafter called the point, which is provided with a tip 19. Openings (not shown) in the point are aligned with the guns. The ring is provided with an

inner edge member 20, the inner surface of which is spherical so that it may slide on the outer surface of the ball 14. The outer end of the ring is provided with a similar internal member 22, the exposed surface of which is spherical to coact with a spherical end portion 24 on the point 18, the latter being urged inwardly against the ring by a hydraulic mechanism to be later described.

10 The ball is made up of an inner ring 26 and an outer ring 28 joined by a sheet-metal, frustoconical portion 30 as well as by an outer spherical portion 32. The inner ring is bolted to a ring-like channel 34 secured inside a corresponding circular opening in the airplane wall 35.

The gun mount is supported at the top by a bracket 36 attached to the outer ring 28 of the ball and at the bottom by a fixed gear segment 38 on top of a limit switch casing 40 which is carried on top of a supporting bracket 42 which extends between the inner and outer rings 26, 28.

Pivoted for movement about a substantially vertical axis 44 is a gun column 46 in the form of an irregularly shaped casting which is supplied with upper and lower pivot pins received within bearings 48 and 50. The upper bearing 48 comprises reversely arranged conical rolls to take the thrust of the column either up or down. This bearing 48 is carried by the bracket 36 while 30 the lower bearing 50 which serves as a pivot is carried on the gear segment 38. Rotation imparted to a pinion 52 engaging the teeth 54 on the gear segment 38 swings this column about its axis 44 to obtain movements of the guns in azimuth and the power for this swinging movement is obtained from a direct current motor 56 mounted on the column and which is connected by reducing gears to the pinion 52.

The gun adaptor 12 is pivoted on the gun column on a horizontal axis 60 to provide movements in elevation and has a gear segment 62 centered on the axis 60 so that changes in elevation may be effected by an electric motor 64 supported on the column 46 and connected by 45 reduction gears (not shown) to a pinion 66 which meshes with the teeth of the gear segment 62. It will be noted from Fig. 2 that the gun adaptor is provided with chutes 68 and 70 which are directly above a passageway 72 provided at the bottom of the bullet-shaped point 18, thus permitting disposal of cartridge casings, belt links and the like. A camera 74 is supported on a bracket attached to the forward end of the adaptor and is pointed at the target through openings 55 76 and 78.

To compensate for the obvious unbalance of the adaptor assembly 12 and the guns 10, an equilibrator has been provided which comprises a cylinder 80 pivotally connected at its right end at the point 100 to brackets 82 upon the gun adaptor. The equilibrator is provided with a piston 84 having a piston rod 86 joined to a yoke 88 pivoted at 90 to the gun column 46. Oil 102 under pressure from an accumulator 92 is delivered through a pipe 94 (Fig. 1) to the cylinder portion 96 which lies at the rod side of the piston 84. The accumulator 92 is supported in a ring-like bracket 98 pivoted to the brackets 82 on the adaptor. The pressure upon the oil 102 within the accumulator 92 is maintained by providing air pressure through a flexible pipe 104 to one side of a flexible diaphragm 106 within the accumulator. The pipe 104 is joined to an air storage tank 108 which is supplied from a motor driven compressor 110. It will be understood that the hydraulic system operating from the accumulator 92 to the cylinder 80 renders it easy to avoid creep. At the same time it is possible to maintain exactly the desired pressure in the accumulator 92 by maintaining a suitable air pressure against the diaphragm 106. As the gun is moved down, the pressure increases in the area 96 but the lever arm between the center 60 and the axis of the cylinder 80 decreases, thus leaving the torque substantially constant.

When the guns are pointed at an extreme angle, the change in relation between the point 18 and the base of the ball 14 effects a change in the straight line distance between the center of the ball 14, for example, and the tip of the point. Some yieldable arrangement must, therefore, be provided for holding the point 18 in contact with the ring 16 and consequently holding the ring 16 against the ball 14. It was found too that the friction between these fairing parts, at or near the positions of considerable angular displacement, was very much increased by any ordinary spring arrangement which might be devised for holding them together and this change was sufficient to greatly increase the load upon the motors 56 and 64 which produce the change in displacement.

Accordingly, a hydraulic system has been provided for holding the point 18 inwardly against the ring 16 and this system includes a hydraulic cylinder 112 which is slidable within an inner tube 114 clamped at 116 to the outer end of the adaptor 12 while the cylinder is attached to the point 18. Surrounding the tube 114 is an outer tube 118 which is slidable on the inner tube and the outer end of this outer tube 118 is fastened to a cross partition 120 in the point 18. On this cross partition 120, are forwardly extending brackets 121 (Fig. 4) holding a pin 122 on which the tip 19 is tiltably secured by means of parallel ribs 123. Rigidly secured to a web between the ribs 123, is a hook 124 (Fig. 3) adapted to engage a cross pin 125 which is secured to the end of the cylinder 112 and this hook may be disengaged by tilting the tip about the pin 122.

Accidental tilting of the tip 19 is prevented by the end of a stub arm 129 on a retaining latch 126 pivoted between ears extending rearwardly from the ribs 123 and connected by a link 127 to a push button 128 at the end of the tip. When it is desired to remove the point 18 of the fairing the button 128 is pushed inwardly against a coil spring thus moving the stub arm 129 aside and permitting the tip 19 to be tilted around its pivot 122 so as to drop the hook 124

from the cross pin 125 at the end of the cylinder. The point 18 and its cap 19 may then be withdrawn axially, with the outer tube 118 sliding on the inner tube 114. When the button is not depressed, its spring urges the latch 126 clockwise, as viewed in Fig. 3, to a position determined by contact of a long arm 131, on the latch, with the pin 122, thus holding the end of the stub arm 129 in such a position over the cross pin 125 that it prevents tilting of the tip 19.

Within the cylinder 112 is a piston 130 connected by a cross pin 132 to the inner tube 114 and hence to the adaptor. Fluid under pressure fills the space between the piston and the left end of the cylinder. As the point portion 18 moves outward with respect to the inner tube 114 the space between the piston 130 and the cylinder head decreases thus increasing the pressure acting to hold portion 18 inward and increasing the friction between portion 18 and the ring 16 and between the ring and the ball 14 with a resulting heavy load on the driving motors as the gun is trained. To avoid this the cylinder 112 is connected by pipes 134 and 136 to a cylinder 138 which is mounted on the adaptor 12 and to a cylinder 140 (Fig. 3) which is mounted on the gun column 46. Each of these cylinders has a piston having an attached roller which rides, in the first instance, against a cam 142 fixed on the gun column 46 and in the second instance, against a cam 144 attached to the gear segment 38 which is mounted on the fixed bracket 42 attached to the plane. By means of this arrangement the pressure within the cylinder 138 and hence in cylinder 112 is held at the desired maximum as the guns are pointed straight to the rear and is decreased as the guns are elevated or depressed, this following from the shape of the cam 142. A similar shape of the cam 144 causes the pressure to be maximum within the cylinder 140 and hence in cylinder 112 when the guns are pointed directly to the rear and decreases this effect as the guns are swung to one side or the other. Consequently, the pressure in the hydraulic system is relieved as the guns and the portion 18 are swung away from center 30 as to maintain a free turning engagement between the point 18 and the ring and between the ring and the ball.

Any suitable system may be employed for the remote control of the motors 56 and 64 so that the guns may be laid or directed at the target in accordance with the wishes of a gunner who operates a sight (not shown) capable of being swung in azimuth and tilted in elevation. During these movements of the gun the pressure which holds together the parts 14, 16 and 18 of the articulated fairing will be automatically controlled so as to prevent the air stream from separating these parts by reason of any undue slackening of the pressure required to hold the parts together and at the same time sufficient pressure will always be maintained within the cylinder 112 to hold them together but without causing any undue friction. The feeding of ammunition to the guns can be carried out automatically by means of any well-known system which delivers the cartridges automatically from a storage receptacle inside the plane itself and allows the links of the conveyor chain as well as the cartridge casings and any duds to fall out through the chute 77.

This application is a division of application Serial No. 26,116, filed May 10, 1948 in my name

for improvements in Remote Control of Guns for Airplanes.

Having thus described my invention, what I claim as new and desire to secure by Letters Patent of the United States is:

1. In an airplane having an opening in its wall, a gun pivotally supported to project through said opening, a sheath covering the gun and surrounding said opening, said sheath comprising sections articulated with respect to one another to permit the gun to be laid, means for drawing in the outer section toward the plane, and means for decreasing the force with which said outer section is drawn in as such section is moved away from a mid position.

2. In an airplane having an opening in its wall, a spherical member secured around said opening and projecting therefrom, a ring fitting and sliding on said spherical portion, a gun supported to project beyond said spherical portion and extending through the ring, an outer fairing about said gun having a spherical joint with the outer end of said ring, a piston and cylinder connection between said outer fairing and the gun, fluid under pressure in said cylinder to draw the fair-

5

ing inwardly, an auxiliary cylinder connected to the first cylinder, and means for decreasing the volume of the auxiliary cylinder as a mid position is reached while increasing its volume as the gun is deflected.

10

3. In an airplane, an opening, a gun projecting from said opening and pivotally mounted for movements with respect to the plane, an articulated sheath surrounding said gun and connected to the plane, and means for holding the parts of said sheath together including means for increasing the holding force as a straight line position is reached and decreasing it during deflection away from that position.

15

4. In an airplane, an opening, a gun projecting from said opening and pivotally mounted for movements with respect to the plane, an articulated sheath surrounding said gun and connected to the plane around the opening therein, and means for holding the parts of said sheath together including means for decreasing the holding force during deflection either in elevation or azimuth.
